UNITED STATES PATENT OFFICE.

JOHN MORTIMER RAYMOND, OF NEW ORLEANS, LOUISIANA.

FLYING-MACHINE PROPELLER.

Application filed October 28, 1921. Serial No. 511,209.

To all whom it may concern:

Be it known that I, JOHN M. RAYMOND, a citizen of the United States, residing at New Orleans, in the parish of Orleans and 5 State of Louisiana, have invented new and useful Improvements in Flying - Machine Propellers, of which the following is a specification.

The object of my present invention is the 10 provision of a simple, efficient and durable propeller, designed more especially, though not necessarily, for use in conjunction with flying machines.

To the attainment of the foregoing, the 15 invention consists in the improvement as hereinafter described and definitely claimed.

In the accompanying drawings, forming part of this specification:—

Figure 1 is a side elevation of the propeller 20 constituting the best practical embodiment of my invention of which I am cognizant.

Figure 2 is a longitudinal section of the same with parts in elevation.

Figure 3 is a plan view with the apertured 25 annulus and the cover removed.

Figure 4 is a broken view of the spiral screen.

Figure 5 is a plan view of the adjusting tie rods.

Similar numerals of reference designate 30 corresponding parts in all of the views of the drawings.

Among other elements my improvement comprises a cone-shaped casing 9. The wall 35 of the said casing 9 is made quite thin as illustrated, and the casing is tapered from one of its ends to a point adjacent to its opposite end as clearly illustrated. In an annulus 4 bolted at 5 to the comparatively 40 large portion of the casing or envelope are formed openings 3 for the entrance of air, and in the center of the cover 2 on the annulus 4 is a cup in which is an appropriate bearing 1. At 10 the casing is provided 45 with exhaust apertures, arranged diametrically opposite each other. It will also be noted that at the inner end of the casing 9 is a conical deflector 15 the apex of which is arranged adjacent to the apertures 10 with 50 a view to deflecting air through the said apertures 10. I would also have it understood at this point that the deflector 15 serves to lend increased strength to the mounting of the small end of the double spiral screw 6 carried by a shaft 14 which is preferably

though not necessarily tubular. Appropriately connected with the small portion of the casing 9 and communicating with the apertures 10 are adjustable elbows 11 60 screwed on ends of outlets 12 and 13 loosely to be set at any angle for driving, lifting or steering. The said outlets 12 and 13 communicate with and extend in diametrically opposite directions from a cylinder 15^x in which the lower end of the casing 9 is disposed.

Appropriately fixed in the casing 9 are 65 annular deflecting baffles 7, Figure 2, designed to prevent too free escape of air thrown against the side of the envelope or casing 9, and also designed to direct such air back into the double spiral screw which extends the full length of the cone-shaped casing or envelope 9, as shown. The baffles 7 being grooved or of channel form in section and the screw 6 being tapered air is compressed in the casing 9 and driven through the lower end thereof.

Fixed on the shaft 14 are lower and upper 70 collars 16 and 17, and movable or adjustable on said shaft 14 in the direction of the length thereof is a collar 19.

The blades of the double spiral screw have 75 lips 19^x at their upper ends to receive rods 20 with eyes 21 at their outer ends. The inner ends of the said rods 20 have arms 22 arranged in and connected to flanges on the collar 19. The rods 15^a include turnbuckles 80 as shown and have inner, lateral arms 23 extending through and connected to flanges on the collar 17. Thus the collar 19 can be 90 properly positioned and adjustably fixed relative to the shaft 14.

At 24 in Figure 1 are rivets through the 95 medium of which the baffles 7 are preferably connected to the casing or envelope 9.

While I show my novel propeller in upright position, it is to be understood that the propeller is susceptible of being used in various positions.

I have entered into a detailed description 100 of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in 105 the future practice of the invention various

changes and modifications may be made such as fall within the scope of my invention as defined in my appended claim.

Having described my invention, what I claim and desire to secure by Letters-Patent, is:—

In a propeller, the combination of a shaft, spiral blades associated with the shaft, rods connected with ends of said blades, a collar

adjustable on the shaft and to which said rods are connected, a collar fixed on the shaft adjusting rods interposed between said collar and the outer ends of the first-named rods, and a casing enclosing said shaft, blades and connections.

In testimony whereof I affix my signature.

JOHN MORTIMER RAYMOND.
